UNITED STATES PATENT OFFICE.

ALFRED LIBERT, OF FOREST-BRUSSELS, BELGIUM.

GIN FOR COTTON AND ALL FIBROUS MATERIALS.

Application filed July 25, 1927, Serial No. 208,314, and in Belgium November 5, 1926.

The present invention relates to an improved gin whereby vegetable textiles, especially cotton fibre and tufts, can be freed from their seeds or other waste.

5 The purpose of said invention lies chiefly in the provision of a machine of simple construction, reliable and yielding more than any similar machines known and hitherto used, capable of thoroughly ginning any textile not detrimental to its fibre.

Cotton gins comprising a gin roller, a doctor knife and a beating shaft rotating in a grid-like trough are generally known.

10 The present invention consists in an improved machine comprising in combination an ordinary gin roller, a spring pressed doctor knife, a beating shaft of polygonal section; each side of the shaft is fitted with a blade or knife and said shaft is surrounded by a cylindrical grid or perforated drum, having a small longitudinal interruption at the side towards the doctor knife and gin roller; said grid is provided with a hopper for feeding the fibrous material inside the grid. The grid 15 will be advantageously formed of two parts hinged together to allow inspection inside. The beating knives will be fitted with brushing elements, such as metallic brushes, resilient metal blades of leather, cardboard, rubber 20 or the like.

This invention has been illustrated in the accompanying drawings, namely:

Fig. 1 an end elevation of said machine;

Fig. 2 a front elevation of same;

35 Fig. 3 a plan view of same;

Fig. 4 a diagrammatical section upon larger scale of the active parts of the machine;

Fig. 5 a section similar to Fig. 4, showing the blades in reversed position.

40 The machine consists of a stationary frame 1 whereupon the usual gin roller 2 has been mounted, this roller being covered either with leather or with paper and the like, and having imparted to it a rapid rotatory movement by means of pulley 3 driven by a belt 4. A sheet metal drum perforated at the bottom A, or circular grating 5, has been mounted tangential to said roller 2, and has a small longitudinal interruption 18 at the side towards 45 the doctor knife and gin roller. Inside this drum-like grating 5 and concentrically thereto, is located a shaft 6 of polygonal section, each side of which is fitted with a beating-knife 7 fixed to it either in plane or in helical arrangement and reaching almost as far as 50 the drum-like grating 5. This shaft 6 has

imparted to it a high-speed rotation of direction reverse to that imparted to roller 2, by means of a pulley 8 driven by a cross belt or cable 9.

55 The knives can be fitted on one of their sides with a brushing element 19 having metallic or fibrous brushes, or they can bear a blade 20 of leather, cardboard, rubber and the like; again they can bear metallic resilient blades as may be necessary for treating special fibrous materials. The grid 5 is made of two parts hinged together at 21 so that it can be readily opened for inspection of the knives.

60 The driving pulleys are preferably mounted upon the same shaft 10 provided with fast and loose pulleys 11. The cotton tufts or flakes are fed uninterruptedly from an open hopper 12 falling inside the drumlike grating 5.

65 A fixed knife 13 hanging vertically from a standard 14 of the frame, is so positioned as to be exactly tangential to roller 2 and fixed drum 5, at their tangential contact, said knife 13 being acted upon by springs 15. On 70 the other side, a wooden batten or blade 16 which is hung down from two chains 17, comes into frictional engagement with roller 2.

75 Any cotton tufts delivered from the hopper are hit by the beating knives 7 and thrown in such a manner as to glide along grating 5 and then reach the gap or interrupted part of said grating, where they are drawn between roller 2 and fixed knife 13; any seeds that have come down to the end of this knife 80 and undergone the action of beating knife 7 are pushed and torn away from their fibre by every one of knives 7 as these pass in succession. The relative position of roller 2 and drumlike grating 5 is variable, as the grating 85 is adjustable and their gap can have exactly the width sufficient to leave free passage upwards to the seeds completely freed from their fibre and to none of the other ones, which latter thus remain in the perforated drum 90 5 and must revert to the cleaning action of roller 2 and fixed knife 13 until every cotton fibre has been taken off them, prior to which the seeds cannot escape; those freed from fibre are let out over the upper edge of the 95 grating as a result of the centrifugal action of beating knives 7, and they may also escape through the holes of grating 5.

100 As to the cotton collected upon the leather surface of roller 2, this is scraped off by the 110 wooden blade 16.

The axes of roller 2 and of shaft 6 are al-

most on a same level, thus providing for an exact position of the fixed knife 13 with respect to the beating knives 7 and for a maximum operating surface of the roller 2.

5 It should be noted that the square-section shaft 6 could be replaced by a hexagonal one or one having any polygonal shape whatever, the number of sides being thus, at will, increased or decreased together with the number of knives 7, whereby the number of operating points will also be modified.

10 Therefore, in the present machine, the number of operating points for every one revolution can range between 1 and any figure, so as not to restrict the number of beating knives 7, i. e. the operating points.

15 The efficiency and yield of said machine in correspondence with any given speed will be thus increased at will.

20 I claim:

1. In a gin for cotton and fibrous material, comprising a ginning roller and a spring pressed doctor knife, a beater shaft of polygonal cross section rotating in opposite direction to the ginning roller, blades secured to each side of said shaft and adapted nearly to contact the ginning roller, brushing ele-

ments fitted on one side of said blades, a cylindrical grid surrounding the beating shaft and having a small longitudinal interruption 30 at the side towards the doctor knife and ginning roller and a hopper forming part of said grid for feeding the fibrous material inside the grid.

2. In a gin for cotton and fibrous material, 35 comprising a ginning roller and a spring pressed doctor knife, a beater shaft of polygonal cross section rotating in opposite direction to the ginning roller, blades secured to each side of said shaft and adapted nearly 40 to contact the ginning roller, brushing elements fitted on one side of said blades, a cylindrical grid surrounding the beating shaft and having a small longitudinal interruption 45 at the side towards the doctor knife and ginning roller and a hopper forming part of said grid for feeding the fibrous material inside the grid, said grid being formed of two parts hinged together about an axis parallel to the beater shaft.

50 In testimony whereof I signed hereunto my name.

ALFRED LIBERT.
